Samuel P. Mason, Killingly, Ct.

Letters Patent

The Schedule referred to in these Letters Patent and making part of the same, containing a description in the words of the said Samuel P. Mason himself of his improvement, in the art of whipping and cleaning cotton.

To all to whom these presents shall come:

Be it known, that Samuel P. Mason of Killingly in the County of Windham and State of Connecticut has invented a new and useful improvement in the art of whipping and cleaning cotton preparatory to the next operation in the manufacture viz picking; and that the following inclusive of the plates hereto annexed is a full and exact description of the construction and operation of the said machine as invented by me viz

Horizontal, Rotary, Stationary, Cotton Whisker
A machine for whipping cotton and cleaning it from seeds & dirt also for breaking the hard bunches very fine, leaving the cotton light and well prepared for picking; illustrated as follows.

Plate 1. Exhibits a vertical projection of the machine A. A. A. A. The frame which may be made of wood or cast iron - B panels which may be fastened to the sides of the frame by means of screws, or otherwise - other from the sides of the machine.

Plate 2. Exhibits the horizontal projection of the machine which is funnel work and in which is formed a throat C between the regular panels, and for the purpose of feeding in the cotton which comes in contact with the stationary pins or fingers by means of the velocity of the Horizontal shafts D. E. as exhibited on Plate 4.

Plate 3. Exhibits a longitudinal section of the machine, to which its throat and the frame A & B as shown on Plate 2, the only unusual work with the exception of the opening C through

which the cotton makes its escape at the end of the boards. At the opposite end of the machine is a door which may be opened at pleasure for the purpose of taking out the dirty sacks &c which by the operation of the machine are separate from the cotton and pass through a circular grating 16 constructed under and partly around the two horizontal shafts. E. E. Said shafts are made of iron or wood with pins or fingers projecting from their centers any distance that the size of the machine may require and revolve with a velocity of 1500 or 2000 revolutions per minute in the direction of the arrows on pulley C.C. - Plate 1, by means of a belt passing under said pulley, and over binding pulley D.

The journals of the shafts run in boxes which are fastened to the side of the frame A, as shown on plates 1 & 2. The pins in the horizontal shafts are so arranged and constructed as to pass near close to corresponding pins or fingers in the four horizontal girts. F. F. A.C. which are equidistant of the frame equidistant from each other around the back shaft, by means of which the hard bunches of the cotton are in the process broken very fine and the dirt and seed separated therefrom and forced through the circular grating while the cotton thus cleaned and whiffed is thrown out at their mouths C. - Plate 1. M. Exhibits the surface of the shaft on a plane showing the arrangement of the pins, which are represented by small circles. M. exhibits the manner in which the pins in the two shafts play into each other. It is a perspective view of the shafts.
